UNITED STATES PATENT OFFICE

2,212,317

WATCH CLEANING MACHINE

Irving Friedman, Newark, N. J., assignor, by direct and mesne assignments, to Efco Manufacturing Company, Newark, N. J., a corporation of New Jersey

Application July 22, 1937, Serial No. 155,029

2 Claims. (Cl. 141—1)

This invention relates to improvements in machines for cleaning watch works and the like, such as, for example, is shown in my copending patent application, Serial No. 90,829, which has matured into Patent 2,104,456, dated January 4th, 1938, of which this application is a continuation in part.

In the cleaning of watches, it is necessary to immerse the works in agitated liquids; inasmuch as the parts of a watch are very small, it is inconvenient and impractical to do this by manual means.

It is therefore an object of this invention to provide a machine for cleaning watch works having a base on which a plurality of containers are secured, one or more of the containers being adapted to contain cleaning fluid and one container being provided with means for thoroughly drying the watch works.

A further object of my invention is to provide the machine with thermal means for drying the watch parts.

A further object of my invention is to provide a machine having a novel holder for the watch works basket, the holder being adapted to be readily secured to or removed from the machine.

A further object of my invention is to provide a watch cleaning machine which is efficient, positive and tamper-proof in operation and permanent in construction.

These and other advantageous objects, which will later appear, are accomplished by the simple and practical construction and arrangement of parts hereinafter described and exhibited in the accompanying drawings, forming part hereof, and in which:

Fig. 1 is a side elevational view of a watch cleaning machine embodying my invention.

Fig. 2 is a top plan view thereof.

Fig. 3 is a fragmentary vertical sectional view showing one of the containers of my machine with a cover secured thereto.

Fig. 4 is a similar, partly fragmentary, view of the drying container of my machine, showing a heating element mounted therein.

Fig. 5 is a top plan view of said container with a heating element and fan mounted therein.

Fig. 6 is a bottom plan view of the cover shown in Fig. 3.

Fig. 7 is an exploded, partly sectional view of the structure for holding watch works in my machine.

Fig. 8 is a perspective view of the correspondingly numbered parts shown in Fig. 7.

Fig. 9 is a perspective view of a holder for

clock works adapted to be used in my machine, and

Fig. 10 is a vertical sectional view of a holder comprising a multiple frame having a plurality of sections, each section being adapted to receive 5 the parts shown in Fig. 8.

Referring to the drawings, the machine embodying my invention comprises a base 1 having an upstanding post 2 and having a plurality of recesses 3 provided with spring members 4 to 10 removably secure containers 5, 6 and 7 within said recesses 3. A fourth container, 8, is preferably molded integral with the base 1; the base has an opening 8' communicating with the interior of container 8, as shown, in Fig. 4. All 15 of the containers are arranged in alignment with the respective sides of the post as shown in the drawings, Fig. 2.

A collar 9 is slidably arranged on the post and is provided with a latch 9' for latching the collar at any predetermined position on the post. The collar has an integral open bracket 10 which is adapted to receive and support an electric motor 11. In order to firmly secure the motor in the bracket 10, the latter may be made in two 25 sections 12, 13, bolted or otherwise secured together tightly about the motor. The motor 11 is connected by a cord 14 or the like to a source of electric current and is operated by a switch 15 or the like. The motor has a depending vertical shaft 16 provided, at its lower end, with a head 17 to which the basket holder 18 may be removably secured.

The holder 18 is adapted to receive the baskets 20 and 22 for watch parts; the baskets are independent of each other and are separated by the member 21; immediate access may be had to either basket to insert or remove watch parts without the danger of intermingling same.

Holder 18 comprises an open frame having 35 spaced rings 18—19, the former defining the uppermost portion of the holder, said rings being designated "upper" and "lower" rings respectively. The basket 22 has a rim 23 which rests on the ring 19. The member 21 is positioned on the ring 19 over the basket rim 23, closing said basket. Basket 20 is suspended from the upper ring 18' and rests on the member 21. Holder 18 is provided with spring fingers 24 having out-turned free ends 25 adapted to be snapped into registry 40 with openings 26 in the head 17, removably securing the holder to the head.

By rotating the collar 9 on the reduced portion 2' of post 2, the bracket 10 may be aligned with any predetermined container and the hold- 45

er 18 may then be brought down within the container and whirled therein.

The containers 5, 6 and 7 contain cleaning fluids F and are provided with baffle members 21, the latter comprising metal bands 28 adapted to expand within the containers and thereby automatically position the baffles therein and having secured thereto, at right angles, rods 29 extending substantially the length of the containers and providing effective baffles for the cleaning fluid F.

The container 8 is used to dry the watch parts after the latter have been cleaned in the containers 5-7. The container 8 has an opening 8' in the bottom thereof so that while the holder 18 is whirled therein air will be drawn up and through the container, facilitating the drying action. The container 8 may be further provided with a heating element 30 adjacent the bottom thereof; in the form shown in Fig. 5 container 8 is provided with a motor-driven fan 31 which forces the air over the heating element 30 and holder 18. The forms of heating elements 30 shown in the drawings are illustrative only; any other form adapted for the same purpose would be within the scope of my invention.

If desired, said heating elements may have thermostatic means incorporated therein to automatically cut off the current when the heating elements have attained a certain degree of heat.

The container 8 is preferably provided with an upstanding stud 32 which forms a stop for the bracket 10 of collar 9. The stud 32 may have incorporated in the upper end thereof an electric switch 33 adapted to be actuated by the weight of bracket 10 and motor 11, to actuate the heating element 30, as well as fan 31 where the latter is used, while the holder 18 is in the container 8. When the holder 18 is in the containers 5, 6, and 7, the bracket 10 rests on and seals the upper edge 34 of said containers, preventing the escape of fumes during the rotation of the holder therein.

The form shown in Fig. 9 is adapted to hold clock works; the basket 20' is provided with spring fingers 24' having out-turned free ends 25' adapted to register with the openings 26 of head 27. The form shown in Fig. 10 enables a plurality of watches to be simultaneously

cleaned; the holder comprises a multiple frame 35 having a plurality of sections 36 each of which is adapted to receive baskets 20 and 22 and member 21, as described in connection with Fig. 7; frame 35 has spring fingers 24' provided with out-turned ends 25' adapted to register with openings 26 of head 27.

The containers 5, 6 and 7 are normally closed by cover members 37 which are provided with spring members 38 to frictionally hold said covers on the containers. The spring members 38, as shown in Fig. 6, are preferably in the form of split rings which are merely snapped into the cover members and by expansion automatically confine themselves therein. Instead of providing the automatic switch 33 incorporated in stud 32 of container 8, a separate electric switch 39 may be arranged in the base 4. The holder 18 may be provided with vanes 40 to complement the baffle action of the baffle rods 29.

The foregoing disclosure is to be regarded as descriptive and illustrative only, and not as restrictive or limitative of the invention, of which obviously many modifications may be constructed, including many embodiments, without departing from the spirit and scope of the invention herein indicated and denoted in the appended claims.

Having thus described my invention, what I claim as new and desire to secure by Letters Patent, is:

1. In a watch cleaning machine, a holder comprising an open frame having spaced upper and lower rings, baskets having rims resting on said rings, and a member positioned on the lower ring 35 over the basket rim thereon, closing said basket, the other basket being suspended on the upper ring directly above said member.

2. In a watch cleaning machine, a holder comprising a multiple frame having a plurality of sections, each section comprising an open frame having spaced upper and lower rings, baskets having rims resting on said rings and a member positioned on the lower ring over the basket rim thereon, closing said basket, the other basket being suspended on the upper ring directly above said member.

IRVING FRIEDMAN.
